UNITED STATES PATENT OFFICE.

ANDREW JACKSON CROWLEY, OF FOLSOM, NEW MEXICO.

WINDMILL.

1,206,514.

Specification of Letters Patent. Patented Nov. 28, 1916.

Application filed September 15, 1915. Serial No. 50,757.

To all whom it may concern:

Be it known that I, ANDREW J. CROWLEY, a citizen of the United States, and a citizen of Folsom, in the county of Union and State 5 of New Mexico, have invented certain new and useful Improvements in Windmills, of which the following is a specification.

My invention relates to wind-mills, arranged to revolve in a horizontal plane, 10 and one of the main objects thereof is to provide such a device which takes advantage of the full force of wind currents by a system of movable vanes which tend to deflect the currents from one to another until 15 the entire force thereof is expended.

My invention is fully described in the following specification, of which the accompanying drawings form a part, in which like characters refer to like parts in each of 20 the views, and in which:

Figure 1 is a sectional plan view of my invention taken on the line 1—1 of Fig. 3, showing the hinged vanes in conditionally assumed positions; Fig. 2 is a section taken 25 on the line 2—2 of Fig. 1; Fig. 3 is a side elevation showing means for locking the vanes; Fig. 4 is an enlarged fragmentary view thereof; Fig. 5 is an enlarged sectional view of the lock; and Fig. 6 is a section 30 taken on the line 6—6 of Fig. 5.

In the drawings forming a part of this application I have shown a wind-mill employing a plurality of hinged vanes yielding in a resilient manner to wind pressures 35 though only to an extent which continues them as operative units of the mill, whereby the wind currents aid instead of retarding the mill operation after they have entered the zone of mill revolution, and continue to 40 so aid the mill operation until the force thereof has been entirely expended or until they have again passed outside of the said zone.

My invention comprises a central shaft 45 7 which is rotatable upon a bearing 8, preferably anti-frictionally as shown, and is stayed by means of guys 9 led to any convenient points, said shaft 7 being illustrated as provided with a gear wheel 10 enmeshed 50 with a pinion 11 on a shaft 12 carried in suitable bearings 13 and having a pulley 14 thereon whence the power generated by the mill may be transmitted to any desired point, this power take-off apparatus being 55 subject, however, to change according to

conditions and forms no part of the invention other than for the purpose stated.

Adjacent the upper end of the shaft 7 I provide four main radial arms 15, 16, 17, and 18, braced by bars 19, 20, 21, and 22, 60 the latter of which serve as supports for four supplemental arms 23, 24, 25, and 26, all of the arms being braced by bars 27 at the outer ends thereof. This arrangement of arms is repeated adjacent the lower end 65 of the shaft 7, and also in a plane intermediate the upper and lower sets of arms, the arms in the same vertical planes bearing the same reference characters though two distinctive and separate wind levels are produced thereby. More than two levels could 70 be produced by multiplying the sets of arms, as will be understood, and the explanation of the operation will be confined to one level and the parts in the several vertical planes 75 will be given the same reference characters.

The main arms are held in horizontally separated relationship by means of vertical bars 15^a, 15^b, 15^c, 16^a, 16^b, 16^c, 17^a, 17^b, 17^c, 18^a, 18^b, and 18^c, respectively, and the supplemental arms are similarly held by means 80 of vertical bars 23^a, 23^b, 24^a, 24^b, 25^a, 25^b, 26^a, and 26^b, respectively, and the brace bars 27 are similarly held by means of vertical bars 7^a. 85

Hinged to the vertical bars 15^a, 16^a, 17^a, and 18^a, are vanes 15^d, 16^d, 17^d, and 18^d, respectively, and similarly hinged to the bars 15^b, 16^b, 17^b, and 18^b, are vanes 15^e, 16^e, 17^e, and 18^e, and similarly hinged to the bars 90 23^a, 24^a, 25^a, and 26^a, are vanes 23^c, 24^c, 25^c, and 26^c, all of which vanes open in the same relative direction. The vanes are normally held in the respective radial planes by means of springs 30 with the exception of 95 the vanes 15^e, 16^e, 17^e, and 18^e, which have coil springs 31 retarding their movement into the respective vertical radial planes, and it will be noted that the closing movement of the vanes is prevented beyond the 100 respective radial planes by the vertical bars in their paths of movement, and the opening movement of the vanes is limited by the vertical bars in their paths of movement in this direction, as is clearly shown in Fig. 1. All of the vanes are adapted to be locked 105 in their respective radial planes by means of locks on their respective closure limiting vertical bars, this being shown fragmentarily in Figs. 4, 5, and 6, each lock consists- 110

ing of a casing 32 containing a spring actuated bolt 33 of the spring latch type which is adapted to be retracted by means of a bell-crank lever 34 having a cable 35 connected with its outer end. These cables 35 are led downward through suitable guiding pulleys 36, Fig. 3, to a ring 37 which is slidably movable on the shaft 7 and is adapted to be forced downwardly by means of a handled cam 38 or equivalent, thus releasing all of the vanes collectively when desired, but I may provide separately operated latches for the individual vanes, or for certain sets of vanes, as will be understood.

Assuming the direction of the wind to be from the bottom of the first sheet of drawings, it will be seen that the vanes 25^e obstruct the wind and the mill turns, each of the outer vanes successively following into this mill operating position, and the mill is turned anti-clockwise. In this movement the vane 18^a had yielded slightly to the wind and the vane 26^e still more so, and the successive vanes in the outer set moving toward the bottom of the sheet yield in this manner in the degree of wind effect thereon. The air currents which had impinged on the vane 25^e were deflected toward the inner vane 18^e and passed between it and the shaft 7 to impinge on the vane 15^e lending its share to the mill revolution, and these currents were again deflected to the vane 16^a and forced the same open against its spring in the degree of wind force, thus again aiding the mill operation. The air currents which cause the vanes approaching the direction of the wind to yield against their springs also pass to the vanes on the far side of the mill, such as 15^a and 23^e, opening them against their springs sufficiently far to impart an angular velocity thereto to aid the mill operation, and these currents being deflected therefrom impinged on the vanes 16^a and 16^e, at an operative angle because of their yielding to the force of the air currents. The wind's force may be expended by this time but, if not, the vanes last named being carried around with the mill into positions of inoperative angularities, the air currents may pass out of the mill on the far side from the direction of the wind. My intent is to have the inner vanes moved toward closure positions against their springs successively as they are carried into the path of the wind in a degree to impart an operative angularity thereto as well as to deflect the air currents toward other vanes which likewise yield to the force thereof, but this yielding being resisted sufficiently by the respective springs to produce the desired results.

The general direction of the arrows in Fig. 1 show the paths of the wind at the moment of beginning mill revolution, as also, as far as possible, their directions

while the mill is revolving, only enough of these arrows having been shown to enable any person skilled in wind-mills to understand the operation of my mill.

When desired, the vanes may all be locked in their respective radial planes and little if any mill revolution occurs because of the balanced resistances on each side of the shaft 7, although it is possible that some degree of revolution might result from the fact that alternate radial arms carry but one vane in each horizontal set of vanes, and this will tend to destroy this balance in slight degree, especially in view of the fact that the inner vanes on the two-vaned arms are normally open and resist closing because of their springs.

My invention therefore consists of a windmill provided with a plurality of sets of hinged vanes, one set opened by the wind against springs and the other set closed against springs by the wind, the degree of closing or opening movement causing deflection of the air currents from vane to vane to take full advantage of the force of the air currents as long as any force exists.

While I have shown a present preferred arrangement of mechanical elements to accomplish the desired results, I do not limit myself thereto, but may make changes thereover, within the scope of the following claims, which do not depart from the spirit of my invention nor sacrifice its advantages.

Having fully described my invention, what I claim as new, and desire to secure by Letters Patent, is:—

1. A wind-mill, comprising a support, a vertical shaft rotatable thereon, a plurality of radial frames carried by said shaft, a vane hinged to the outer edge of each frame and movable into and to one side of the plane of its frame, a spring for resiliently resisting movement of each vane out of the plane of its frame, a supplemental vane hinged at its outer edge to alternate frames between said first named vanes and said shaft, and movable into and to one side of the plane of its frame, and a spring for resiliently resisting movement of each supplemental vane into the plane of its frame.

2. A wind-mill, comprising a support, a vertical shaft rotatable thereon, a plurality of radial frames carried by said shaft, a vane hinged to the outer edge of each frame and movable into and to one side of the plane of its frame, a spring resiliently resisting movement of each vane out of the plane of its frame, a supplemental vane hinged at its outer edge to certain of said frames between said first named vanes and said shaft and movable into and to one side of the plane of its frame, a spring resiliently resisting movement of each supplemental vane into the plane of its frame, and means for locking each vane to its frame.

3. A wind-mill, comprising a support, a vertical shaft rotatable thereon, a plurality of radial frames carried by said shaft, a vane hinged to the outer edge of each frame and movable into and to one side of the plane of its frame, a spring resisting movement of each vane out of the plane of its frame, a supplemental vane hinged at its outer edge to certain of said frames between said first named vanes and said shaft, a spring resisting movement of each supple-

mental vane into the plane of its frame, means for locking each vane to its frame, and means common to all said vanes for unlocking the same.

In testimony whereof I have signed my name to this specification in the presence of two subscribing witnesses.
